UNITED STATES PATENT OFFICE.

JOSEPH MADDEN, OF DUBLIN, IRELAND.

REVOLVING REVERSIBLE SEAT.

1,007,217.

Specification of Letters Patent. Patented Oct. 31, 1911.

Application filed December 30, 1910. Serial No. 600,074.

To all whom it may concern:

Be it known that I, JOSEPH MADDEN, of 48 Capel street, Dublin, Ireland, boot and shoe manufacturer, have invented new and 5 useful Improvements Relating to Revolving Reversible Seats; and I do hereby declare that the following is a full, clear, and exact description of the same, reference being had to the accompanying drawings, 10 forming a part hereof.

This invention has reference to revolving reversible seats, and in order that my invention may be readily understood and carried into effect I will now proceed to describe the 15 same fully with reference to the accompanying drawings in which:

Figure 1 is a transverse section through a seat embodying my invention and taken on the line 1—1 of Fig. 2. Fig. 2 is a 20 longitudinal section through the same. Fig. 3 is a view of the shade or awning herein- after described.

In carrying my invention into effect I 25 journal in suitable end supports or frames *a* a spindle *b* upon which is mounted the seat composed of wooden bars or fillets *c* secured to end pieces *d* through which the spindle *b* passes.

The end pieces *d* are built up of a central 30 frame *d'* suitably apertured as at *b'* for the spindle *b*, and formed with its periphery as trough shaped grounds for the foundation of a trough *e*, and which is held in place by a one piece stay *d''* complementally 35 formed as clearly shown in Fig. 1. The stays *d''* form the base to which the bars *c* are secured.

In each of the end pieces *d* I form a water 40 channel *e* which may be made of zinc or other suitable material and having holes *f* forming outlets. The end supports or 45 frames *a* are formed with arm rests *g* and a back rest or supopr *h* is also provided which may be pivoted upon the spindle *b* so that it may be swung from side to side. The said end supports are provided with brackets *i* serving to support standards *i'* to

which the awning or shade *j* may be attached. This awning is preferably constructed as shown in Fig. 3 and comprises 50 a frame *k* covered with suitable fabric said frame having a socket *l* adapted to fit over a pin *m* projecting from a bar *n* which is arranged between the standards *i* said bar *n* having a pin *o* at each end adapted to fit in 55 holes formed at the top of each stand.

Suitable binders or stays such as *p* serve to connect the end frames *a* rigidly together. Suitable means such as a pin or catch may be provided for retaining the seat in the de- 60 sired position.

It will be seen that a seat constructed in accordance with my invention may be readily reversed or revolved around its spindle thus always providing a dry seat for use 65 rain or moisture being conducted away from the top side by means of the aforesaid water channels.

What I do claim as my invention and desire to secure by Letters Patent is:— 70

A rotatable reversible seat comprising, a suitable support, and a seat structure rotatably carried by said support, said seat structure including a plurality of spaced apart symmetrical polygonal shaped frame 75 members arranged about a common axis of rotation, each having its periphery provided with trough shaped grounds, a continuous covering of material formed to the periphery of said frame members and connecting 80 the same to form troughs, a one-piece stay for each of said frame members cut to fit the periphery of said covering with cut out portions at the V of the said trough formed thereby, and a plurality of seats secured to 85 said stay, one above each of the said troughs, combined substantially as described.

In testimony whereof I affix my signature in presence of two witnesses.

JOSEPH MADDEN.
